UNITED STATES PATENT OFFICE.

JOHN SAVIN, OF LIVERPOOL, ENGLAND, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed January 12, 1921. Serial No. 436,664.

To all whom it may concern:

Be it known that I, JOHN SAVIN, a subject of the King of Great Britain and Ireland, and a resident of Liverpool, England, 5 have invented certain new and useful Improvements in Automatic Telephone Systems, of which the following is a specification.

The present invention relates in general to 10 automatic telephone systems in which connections are established through the medium of mechanical switching devices at the exchange, but is more particularly concerned with systems of this type which are of small 15 capacity, such as are commonly used in the so called private branch exchanges. The present invention may be considered as being an improvement on or a modification of the system shown in the pending application 20 of Winfred T. Powell, Serial No. 161,957 filed April 14, 1917.

The object of the present invention is to provide a simple and inexpensive automatic exchange, capable of dealing with up to 40 25 lines or more, without involving the use of large capacity switches such as the 100 line connectors used in the Strowger automatic telephone system.

According to the present invention, two 30 step by step switches of the type, having no release movement, that is to say, of the type in which every movement of the switch is controlled by the rotary stepping magnet, are linked together in such a manner, that 35 one of said switches is adapted to act as a finder switch to move from the line of the party previously using the switch, to the line of the next party calling, and establish connection therewith, while the other switch 40 is adapted to act as a connector to establish connection under the control of the calling party, with the line of the party required, and subsequently to move to a normal position corresponding to the position from 45 which it started, under the control of its own stepping magnet, on the completion of the call.

Further features of the invention will be better understood by referring to the accompanying drawings, in which, Figure 1 shows 50 a diagram of connections of the calling side of the exchange illustrating the arrangement of finder switches and the grouping of subscribers, Figure 2 shows a circuit diagram for operating the connector to estab-

lish the connection desired, while Figure 3 is a diagrammatic representation of the numbering scheme of the exchange system described.

It will be assumed that substation A is 60 making a call, to do this he lifts his receiver 1 thereby closing the following circuit: earth, armature 2 of relay 3 and its resting contact, resting contact of armature 4 of relay 5 and said armature, line 6 to substation 65 A and back through line 7 to armature 8 and its resting contact, lower winding of relay 5, windings 9 and 10 of relay 11 to battery. In this circuit relay 11 energizes 70 and short circuits its high resistance winding 70 10 at is armature 12 and connects battery to the relay 13 by its armature 14. Relay 13 energizes and connects earth at its armature 15 to the starting wire 16 of the finder switch B, whereby if the switch is free, the 75 relay 3 is energized. Armatures 2 and 17 and 18 are thereby operated, the former to connect earth to one side of the winding of high resistance relay 19, the other side of 80 which relay is connected to the stepping magnet 20, while armature 17 connects the junction of the stepping magnet 20 with relay 19 through armature 21 and its resting contact to private wiper 22 of the finder switch. 85

Now normally all the private contacts of the finder switch are connected to earth via armatures 23, 23' of relays 5, 5' etc., individual to the different subscribers, but in the case of the calling party when the relay 11 has operated to short circuit its high resistance winding 10, the current through the lower winding of relay 5 is increased 90 sufficiently to cause the armature 23 to move from its resting to its working contact. The armature 23 is controlled by a lighter spring than the other armatures 4 and 8 of relay 5 so that these latter armatures are not affected by this current. The consequence of this arrangement is that if the 95 wiper 22 is not resting on the contact of the calling line, which would only be the case if the calling man had been the last to use that switch, it will be earthed so that the high resistance relay 19 will be short circuited and the stepping magnet 20 will 100 operate. This will continue as long as the wiper 22 is earthed but as soon as it reaches the line of the calling party, earth will be 105 missing and as the relay 19 is no longer 110

short circuited, it will operate in series with the magnet 20; while the magnet 20 will not operate on account of the high resistance of relay 19. Relay 19 on operating 5 connects wipers 24 and 25 by means of its armatures 26 and 27 to the upper and lower winding respectively of line relay 28 of connector switch C (Figure 2), which relay energizes in the following circuit, earth, 10 lower winding of relay 28, armature 27 and its working contact, wiper 25, line 6, substation A, line 7, wiper 24, armature 26 and its working contact, upper winding of relay 28 to battery. Armature 29 of this relay 15 connects earth to the winding of relay 30 which energizes and at armature 31 connects earth back over line 34 to armatures 32 and 35 of relay 19 to maintain relays 36 and 19 energized after relay 3 has deenergized. 20 Relay 36 which energized originally on the energization of relay 19 through the circuit earth; armature 2 and its working contact, armature 32 and its working contact, armature 35 and its working contact, relay 36 to 25 battery, disconnects the starting wire 16 from relay 3 and transfers it on the deenergization of said relay through armature 18 to the starting wire 37 leading to the next finder switch. Armature 21 of relay 19, on 30 said relay energizing connected earth to wiper 22 and thence through armature 23 and its working contact to private normal 38 and to the upper winding of relay 5. In this circuit relay 5 operates fully and 35 connects the lower winding of relay 5 and relay 11. Relay 11 deenergizes, somewhat sluggishly in view of its winding 10 being short circuited, and at armature 14 breaks the circuit of relay 13 and disconnects earth 40 from the starting wire, prior to the deenergization of relay 3 and therefore before the starting wire 16 is connected through to starting wire 37 of the next switch.

Before proceeding with the description of 45 the connector switch C, a description will first be given of the grouping of the substations with relation to the finder switches.

For convenience, it will be assumed as 50 shown in the system illustrated, that the capacity of the system is 39 local lines and four exchange lines while the finder switches have a capacity of 25 lines.

It should be mentioned that the connector switches which are of similar construction 55 to the finder switches, have two banks, each having a capacity of 25 lines. These two banks are wiped over by two sets of wipers driven by a common motor magnet and preferably arranged on the same shaft. As 60 one bank of the connector switch can deal with 21 local lines, and the other bank can deal with 18 local and 4 exchange lines, as indicated in the diagrammatic numbering scheme, Figure 3, it is convenient to divide 65 the finder switches into two groups one for

the former and the other for the latter set of lines. The number of finder switches provided for each set of lines will, of course, depend on the traffic requirements. For convenience, it will be assumed that two 70 finder switches are sufficient for each set of lines. These lines would in turn be divided into groups, for instance, ten sub-stations being normally allotted to one finder switch and eleven to the other in the 75 first set, although obviously the arrangements may be modified as desired. The advantage of this subdividing is that usually subscribers of one group would use one switch, while subscribers of the other group would use the other switch, although in cases of two subscribers of one group requiring finder switches at about the same time, the last subscriber would be able to utilize the finder switch normally associated 80 with the other group. Consequently, if when subscriber A had made a call the line finder B was in use, the starting wire 16 would be connected via the working contact of armature 39 of relay 36, resting contact of armature 18 to starting wire 37, resting contact of armature 39' of relay 36' of 85 finder switch B' to relay 3' to set this switch in operation. If finder switches B and B' were both engaged simultaneously the call 90 would be held up, but in order that the number of times this occurs may be ascertained, a relay 40 is provided which energizes on the simultaneous energization of 95 relays 36 and 36' through the circuit, earth, 100 armature 41, armature 41', relay 40 to battery, and thereby closes the circuit through armature 42 and its working contact to meter 43. If this occurs frequently, it indicates that an additional finder switch is 105 required.

If a subscriber in the group allocated to 110 finder switch B' should make a call when said switch is engaged, the starting wire circuit is transferred through working contact of armature 39' of relay 36' through resting contact of armature 18' of relay 3' to starting wire 16 of finder switch B.

It should be mentioned that relays 11 and 115 13 are common to the group of substations allocated to finder switch B, while relays 11' and 13' are common to the group of substations allocated to finder switch B', while relay 5' is the cut-off relay of a substation of the same group as substation A.

Having described the various arrangements controlling the connection of the calling subscriber to the finder switch, a description will now be given of the circuits 120 governing his connection to the party he desires.

Assume he wants connection with substation 106, he will first operate his dial switch to produce one interruption, that is to say, 125 the relay 28 will be deenergized once, while 130

relay 30 being of the slow to release type will remain energized. Consequently, a circuit will be closed from earth, through resting contact of armature 29, working contact of 5 armature 44 of relay 30, series relay 45, armature 46 of relay 47 and its resting contact, armature 48 of relay 49 and its resting contact, magnet 50 to battery. Magnet 50 therefore steps the switch round one step 10 from the normal position shown. Wiper 51 is thereby connected to earth, the first contact from normal in this bank being earthed. When the slow series relay 45 falls back a short time after the transmission of 15 the first digit, as the first digit was one, the following circuit will be closed, earth, wiper 51, armature 52 of relay 45 and its resting contact, relay 53 to battery. Relay 53 operates and locks operated through its armature 20 54 and its working contact to earth on armature 31 of relay 30; while armatures 55, 56, 57 switch over from their normal connection to wipers 58, 59, 60 to wipers 61, 62, and 63 so that the lower bank of contacts is taken into use in place of the upper set.

Obviously if the first digit dialled had been other than 1, as the relay 45 remains energized throughout the transmission of a 30 series of impulses and as only the first contact from normal in the bank of contacts swept over by wiper 51 is earthed, it would be impossible for relay 53 to be energized and consequently, the upper set of wipers 25 would be taken into use. In order therefore, to obtain access to the lower bank, it is necessary that the number of the parties connected to that bank should be prefixed by the digit 1. The next digit to be dialled is 40 0 (ten impulses) and the circuit of the stepping magnet will be closed as before and the wipers will be stepped round ten more steps to the eleventh contact from normal. Figure 3 is a diagrammatic representation of 45 the numbering scheme of the exchange system described. The left hand representation gives the position of the subscriber's connections with their corresponding numbers in the upper bank of contacts and the 50 right hand representation gives the position of the subscriber's connections in the lower bank of contacts. From these positions it will be seen that the eleventh contact corresponding to the number 10 is dead so that 55 when the wipers come to rest on this contact, nothing happens and the subscriber can dial again. This time he sends six impulses, causing the stepping magnet to move the switch round so that private wiper 63 60 will make connection with private contact of substation number 106. Now if wiper 63 comes into engagement with an earthed contact, the following circuit will be closed, earth, wiper 63, resting contact of armature 64 of relay 65 and said armature, working

contact of armature 57 and said armature, armature 66 of relay 45 and its working contact, resistance 67, resting contact of armature 68 of ringing trip relay 69, upper winding of relay 49 to battery. Consequently, relay 49 energizes every time wiper 63 passes over an earthed contact. This is of no consequence during the transmission of impulses as relay 45 at armature 70 puts a short circuit about the armature 48, but 75 if the wiper 63 is resting on an earthed contact when relay 45 deenergizes after the transmission of a series of impulses, that is to say, if the party called is engaged, then the relay 49 will be locked energized 80 through the contact springs controlled by armature 66, which are arranged to make contact before armature 66 breaks contact, working contact of armature 71 and said armature, working contact of armature 31 85 to earth; relay 49 at armature 72 connects the busy tone transformer 73 to one of the line conductors informing the calling subscriber that the line is engaged. The subscriber then hangs up his receiver, thereby 90 breaking the circuit of relay 28 which de-energizes and is followed by the deenergization of relay 30. Relays 49, 53, 36, 19 and 5 also deenergize, due to the removal of the holding earth by armature 31 of relay 95 30. Armature 31 also connects earth to all the contacts in the bank swept over by a wiper 74 except the first or normal contact, so that a circuit is closed for the stepping magnet 50 as follows, earth, wiper 74, magnet interrupter springs 75, resting contact of armature 89 of relay 65 and said armature, series relay 45, armature 46 and its resting contact, armature 48 and its resting contact, magnet 50 to battery. Magnet 50 100 therefore operates and continues to operate until the wiper 74 reaches the normal un-earthed contact, that is to say, when the connector is in its home position, so that both the finder switch and connector switch 105 110 are in readiness for another call.

If, on the other hand, the party called was not engaged, there would have been no earth on wiper 63 and relay 49 would not be energized at the time relay 45 permitted its 115 armature 66 to fall back. In this case the following circuit would be completed, earth, armature 31 and its working contact, armature 71 and its resting contact, upper winding of relay 47, resting contact of armature 66 and said armature, armature 57 and its working contact, armature 64 and its resting contact, wiper 63, winding of cut-off relay of called line (see relay 5, Figure 1) to 120 battery. Relay 47 and the cut-off relay of the called line energize over this circuit, the latter to cut-off the starting relay circuit while relay 47 locks itself energized at armature 75 to earth on armature 31, closes the ringing circuit through the called station 125 130

at armatures 76 and 77 and prevents further dialling affecting the stepping magnet by opening its circuit at armature 46. The ringing circuit may be traced as follows, 5 earth, ringing generator 78, working contact of armature 79 of ringing interrupter relay 80, and said armature, resting contact of armature 87 and said armature, armature 76 and its working contact, armature 56 and its working contact, wiper 62, called subscriber's line and ringer back to wiper 61, armature 55 and its working contact, armature 77 and its working contact, upper winding of relay 69 to battery. 10 15 Relay 69 is designed not to energize when the subscriber's receiver is on the hook, but to energize immediately the receiver is removed, either with direct current alone or with direct current and ringing current together. Consequently, as soon as the called party lifts his receiver, relay 69 energizes, and disconnects ringing current at armature 87, locks itself energized at armature 82 to earth on armature 83 of relay 30 and connects the calling line through condensers to the called line at armatures 87 and 68. Current is then fed through relay 49 to the called subscriber's loop for speaking purposes, while relay 47 at armature 100 connects earth direct to wiper 63 so as to maintain the line engaged. Conversation can then be carried on in the usual way, while the release is under the control of the calling subscriber, who, on hanging up his receiver, effects the deenergization of relays 28, 30 35 which occurs when a local subscriber's line is seized except that the relay 94 is substituted for the cut-off relay of the local subscriber. Consequently, the same sequence of operations occurs assuming that the exchange is of the magneto type, if not, arrangements would be provided so that each exchange line would be called in the appropriate manner, the calling means being set in action by the ringing generator.

The operation of relay 94 connects earth via armature 95 and its working contact, to a common lead connected to the working contacts of the armatures 90 of relays 33 of the various connector switches in the exchange.

This arrangement is provided so that if the first exchange line called should be engaged when the number 100 is called the stepping magnet 50 will be automatically energized after the cessation of the dialling, to step the wipers round until a free exchange line can be found. The circuit may be traced as follows:—earth, armature 95 of relay 94 and its working contact, (relay 94 being of course, individual to the trunk line), armature 90 of relay 33 and its working contact, contact 96, wiper 74, interrupter springs 75, resting contact of armature 89 and said armature, series relay 45, resting contact of armature 46 of relay 47 and said armature, armature 48 and its resting contact or armature 70 and its working contact, stepping magnet 50 to battery. Consequently, series relay 45 will be maintained operated and magnet 50 will automatically make an additional step; if the next exchange line is also engaged, a similar circuit will be closed via armature 97 of relay 98 and its working contact, armature 91 and its working contact to contact 99 and wiper 74 from where the circuit continues as before. The consequence is, that the series relay 45 will not deenergize and the magnet 50 will be continuously operated until an idle line is found. On an idle line being found, the magnet 50 will cease to operate and relay 45 will deenergize to close the circuit of the upper winding of relay 47 and the relay of the selected line corresponding to relays 94 and 98. Relay 47 locks energized and connects earth direct to wiper 63 by means of armature 100. The operation is identical with that described above.

If all the exchange lines should be engaged, it will be noted that no armature is provided to the last relay 101, so that the last contact in the bank wiped over by wiper 74 will not be earthed, even if the line corresponding to it is busy.

On the other hand, as the line is busy the wiper 63 will be earthed, and so the busy tone will be sent back to the calling subscriber similarly to what occurs in the case of a local line which is found to be engaged.

If it is desired that conference facilities should be provided, the number 004 should be allocated for this purpose. An impedance 102 is placed across the line contacts wiped over by wipers 58 and 59 while a permanent potential is placed on the corresponding private contact 103 by means of battery fed through a resistance 104, individual to the connector. The consequence is, that the line is always accessible and as many people may confer as there are connectors in the system.

It will be appreciated therefore, that a comparatively cheap and inexpensive small exchange system has been evolved, utilizing apparatus already used in connection with larger exchanges and capable of providing numerous facilities. At the same time it should be appreciated that the invention is not limited to the particular apparatus described, nor to the circuits shown, as considerable modifications may be made therein without departing from the spirit of the invention as set forth in the appended claims.

Having now particularly described and ascertained the nature of my said invention, and in what manner the same is to be performed, I declare that what I claim is:—

1. In an automatic telephone system, two groups of subscribers lines, two link circuits at the exchange, a finder switch at one end of one link circuit having access to the lines in only one of said groups, a finder switch at one end of the other link circuit having access to the lines in the other group but not to the lines in the first group, and a connector switch at the opposite end of each link circuit, and wipers for each connector having access to all the lines of both groups and having movement in one direction only.

2. In a branch exchange, a line finder connector link for connecting calling and called lines, main exchange trunk lines accessible to said connector, some of the subscribers' lines being denied access to said trunk lines, a relay in said connector for preventing connection with one of said trunk lines, and a circuit for said relay including a wiper of said finder.

3. In an automatic switch, two sets of wipers, line contacts accessible to one set of wipers and numbered from 2 to 9, correspondingly positioned line contacts accessible to the wipers of the other set and numbered from 11 to 18, and a wiper switching contact located ahead of the first contact in the second set.

4. In an automatic switch, two sets of wipers, line contacts accessible to the wipers of one set, similarly numbered line contacts accessible to the wipers of the other set, the second set of line contacts being displaced a distance of one contact with respect to the

contacts of the first set, an additional line contact accessible to the wipers of the first set ahead of the other line contacts, and a wiper switching contact located ahead of all 5 the line contacts of the second set.

5. In an automatic switch, two sets of wipers, a wiper selecting relay, stepping mechanism responsive to impulses delivered to said switch to advance both sets of wipers 10 simultaneously, and a circuit for said relay closed by one of said wipers when advanced from normal position.

6. In an automatic switch, two sets of wipers, wiper selecting mechanism, operating mechanism in said switch for advancing said wiper sets simultaneously in a plurality of stages, and a circuit for controlling said selecting mechanism closed by one of said wipers in the first stage of its operation. 20

7. In an automatic rotary switch of the adding type, two sets of wipers, mechanism for advancing said wiper sets simultaneously in a plurality of separate movements, 25 each movement comprising one or more steps of equal length, and wiper selecting mechanism controlled by a wiper in one of said sets in the first movement thereof.

8. In an automatic rotary switch of the

adding type, two sets of wipers, one set being normally connected for use, means for advancing said wiper sets simultaneously in a plurality of separate movements, each movement comprising one or more steps of equal length, a wiper switching relay for disconnecting said one set of wipers and for connecting the other set, and a circuit for said relay closed by a wiper in one of said sets upon the first movement thereof provided the first movement comprises a 40 particular number of steps.

9. In a branch exchange, a link circuit for connecting calling and called lines comprising a line finder and a connector, main exchange trunk lines accessible to said connector, some of said subscriber's lines being denied access to said trunk lines, a service restricting wiper in said finder, contacts associated with said wiper connected to a source of current or not connected at all, depending on whether the corresponding lines are denied access to said trunk lines or not, and means in said connector controlled by said wiper for preventing connection with said trunk lines.

Signed by me at Liverpool, England, this 10th day of December, 1920.

JOHN SAVIN.
